Primary Examiner—Louis S. Zarfas*Assistant Examiner*—Inga-Maria Hyttinen*Attorney, Agent, or Firm*—Mark R. Wisner[57] **CLAIM**

The ornamental design for a floating fish attracting light, as shown and described.

DESCRIPTION

FIG. 1 is a perspective view of a floating fish attracting light showing my new design from the top, one end, and one side; FIG. 2 is a top plan view of the design shown in FIG. 1; FIG. 3 is a side elevational view of the first side of the design of FIG. 1;

FIG. 4 is an end elevational view of the first end of the design of FIG. 1;

FIG. 5 is a bottom plan view of the design shown in FIG. 1; FIG. 6 is a side elevational view of the second side of the design of FIG. 1; and,

FIG. 7 is an end elevational view of the second end of the design of FIG. 1.

The cable in FIGS. 1, 2, 4, and 5 is shown broken away to indicate indeterminate length.
